(57) **CLAIM**

The ornamental design of an unmanned marine surface vessel, as shown and described.

DESCRIPTION

FIG. 1 is a perspective view of an unmanned marine surface vessel;

FIG. 2 is a bottom perspective view of the unmanned marine surface vessel;

FIG. 3 is an elevated side view of the unmanned marine surface vessel;

FIG. 4 is an elevated front view of the unmanned marine surface vessel;

FIG. 5 is an elevated rear view of the unmanned marine surface vessel;

FIG. 6 is an elevated top view of the unmanned marine surface vessel; and,

FIG. 7 is an elevated bottom view of the unmanned marine surface vessel.

In the drawings, the broken lines represent unclaimed portions of the unmanned marine surface vessel and form no part of the claimed design.
